CLAIM

The ornamental design for a tote, as shown and described.

DESCRIPTION

FIG. 1 is a top perspective view of the design of a tote showing the new design;

FIG. 2 is a bottom perspective view of the tote shown in FIG. 1;

FIG. 3 is a right side elevation view of the tote shown in FIG. 1 (the left side elevation view of the tote is a mirror image of the view shown in FIG. 3);

FIG. 4 is a front elevation view of the tote shown in FIG. 1 (the rear elevation view of the tote is a mirror image of the view shown in FIG. 4);

FIG. 5 is a top perspective view of the design of a second embodiment of a tote showing the new design;

FIG. 6 is a bottom perspective view of the tote shown in FIG. 5;

FIG. 7 is a right side elevation view of the tote shown in FIG. 5 (the left side elevation view of the tote is a mirror image of the view shown in FIG. 7); and,

FIG. 8 is a front elevation view of the tote shown in FIG. 5 (the rear elevation view of the tote is a mirror image of the view shown in FIG. 4).
